United States Patent Office

Des. 193,314
Patented July 31, 1962

193,314

BOTTLE CARRIER

Mila Mangold, 2954 Magnolia St., Berkeley, Calif.

Filed May 29, 1961, Ser. No. 65,389

Term of patent 14 years

(Cl. D58—26)

Fig. 1.

Fig. 2.

Fig. 3.

Fig. 4.

I claim:

The ornamental design for a bottle carrier, as shown and described.
